UNITED STATES PATENT OFFICE

116,039

DESIGN FOR A COMB

Paul S. Madsen, Bethany, Conn., assignor to The Seamless Rubber Company, Incorporated, New Haven, Conn., a corporation of Massachusetts

Application May 31, 1939, Serial No. 85,276

Term of patent 7 years

To all whom it may concern:

Be it known that I, Paul S. Madsen, a citizen of the United States, residing in Bethany, in the county of New Haven and State of Connecticut, have invented a new, original, and ornamental Design for a Comb, of which the following is a specification, reference being had to the accompanying drawing, forming part thereof, in which

Fig. 1 is a face view of a comb embodying my new design;

Fig. 2 is an end elevation looking from the right-hand end of Fig. 1; and

Figs. 3, 4 and 5 are sections on lines 3—3, 4—4 and 5—5, respectively, of Fig. 1.

I claim:

The ornamental design for a comb, substantially as shown.

PAUL S. MADSEN.
